(57) **CLAIM**

The ornamental design for a multiple mode work light, as shown and described.

DESCRIPTION

FIG. 1 is a front perspective view of a multiple mode work light, showing our new design;

FIG. 2 is a back perspective view thereof;

FIG. 3 is a front view thereof;

FIG. 4 is a back view thereof;

FIG. 5 is a top plan view thereof;

FIG. 6 is a bottom plan view thereof;

FIG. 7 is a right side view thereof; and,

FIG. 8 is a left side view thereof.

The broken lines shown in the figures illustrate portions of the multiple mode work light that form no part of the claimed design.

1 Claim, 6 Drawing Sheets
